United States Patent Office.

ELIAS BROWN, OF WAPPINGER'S FALLS, NEW YORK.

Design No. 4,523, dated December 20, 1870.

DESIGN FOR A TUCK-COMB.

The Schedule referred to in these Letters Patent and making part of the same.

I, ELIAS BROWN, of the town of Wappinger's Falls, Dutchess county, and State of New York, have invented and produced a new and original Design for Ladies' Tuck-Combs, of which the following is a specification.

The nature of my design is fully represented in the accompanying drawing, to which reference is made, and is appropriate for either shell, rubber, horn, or any kind of material from which combs are made, the intention being to represent, to some degree, a "fly."

Claim.

I claim as my invention—
The design for a tuck-comb, as shown and described.

ELIAS BROWN.
